UNITED STATES PATENT OFFICE.

PETER J. GORDON, OF NEW YORK, N. Y., ASSIGNOR TO H. A. CARY COMPANY, OF NEW YORK, N. Y.

DESIGN FOR A DISH.

SPECIFICATION forming part of Design No. 35,879, dated April 22, 1902.

Application filed March 25, 1902. Serial No. 99,941. Term of patent 3½ years.

To all whom it may concern:

Be it known that I, PETER J. GORDON, a citizen of the United States, and a resident of the city of New York, borough of Manhattan, in the county and State of New York, have invented and produced a new and original Design for a Dish, of which the following is a specification, reference being had to the accompanying drawings, forming a part thereof, in which—

Figure 1 is a side elevation of a dish embodying the features of my design, and Fig. 2 is a central transverse section of the same on the line 2 2 in Fig. 1.
15 The leading features of the design consist in a simulation of a dromedary or camel in a kneeling position, its legs and lower portion of the body forming the base of the dish and its neck and head the handle; but the mouth 20 of the dish, which is at the upper portion

of the back of the simulated dromedary or camel, presents a concave outline.

The minor feature of the design consists in the outline of the mouth of the dish, extending from a point above the neck of the simulation of the dromedary or camel to the back line of the animal. 25

Having thus described my invention, I claim as new and desire to secure by Letters Patent—

The design for a dish herein shown and described. 30

In testimony whereof I have signed my name to this specification in the presence of two subscribing witnesses.

PETER J. GORDON.
